UNITED STATES PATENT OFFICE.

WALTER THIEM, OF HALLE-ON-THE-SAALE, GERMANY, ASSIGNEE TO SVEND OLSEN,
OF HALLE-ON-THE-SAALE, GERMANY.

APPARATUS FOR THE PRODUCTION OF AIR-GAS.

1,071,276.

Specification of Letters Patent. Patented Aug. 26, 1913.

Application filed April 28, 1911. Serial No. 623,958.

To all whom it may concern:

Be it known that I, WALTER THIEM, a subject of the King of Prussia, and residing at Halle-on-the-Saale, German Empire, have invented certain new and useful Improvements in Apparatus for the Production of Air-Gas, of which the following is a specification.

This invention relates to oil feeding devices particularly as applied for the manufacture of air-gas, for illuminating and heating purposes, from the lighter hydrocarbons, the air and the hydrocarbon being introduced into the carbureting-chamber in definite proportions.

To prevent the direct passage of the hydrocarbon vapor from the vessel containing the hydrocarbon into the carbureting-chamber, it has been the practice to employ a so-called siphon seal. This prevents the volume of already manufactured gas in the carbureting-chamber from being enriched to excess on stoppage of the plant, or on a considerable change of temperature occurring. The employment of such a siphon (for instance in the form of a U-shaped pipe), has, however, the drawback that the sealing-liquid (readily evaporated fuel) contained in the siphon is also exposed to evaporation. Thus the seal is destroyed as soon as this liquid has been evaporated, for instance through the plant remaining out of use for a considerable interval. To overcome this defect, I provide between the hydrocarbon reservoir and the carbureting-chamber a vessel containing a sealing-liquid which is non-evaporable, or only slightly evaporable, whereby a permanent vapor-tight closure between the hydrocarbon reservoir and the carbureting-chamber is insured.

A preferred embodiment of my invention is illustrated in the accompanying drawing, in which—

Figure 1 is a front elevation of the apparatus, certain parts being shown in section. Fig. 2 is a longitudinal section through the apparatus. Fig. 3 shows in section, on a larger scale, the sealing vessel employed between the hydrocarbon reservoir and the carbureting-chamber, and Fig. 4 shows in perspective view the structure by which the scoop is operated.

The apparatus consists of a tank *a*, in which there is mounted in well-known man-

ner a rotary blower *b*, which acts as a pump to suck air into and through the carbureter, and resembles the drum of a gas-meter. The blower *b* is revolved by means of toothed gears *c*, *d*, the latter one of which is driven by means of a rope-drum *e*. The gas-holder *g* is supported by the hood *f*, which covers the blower *b*. On the blower being set in motion, it draws in air, which enters at the inlet *i* and passes through the sinuous, flat, sheet-metal duct *h*, which constitutes the carbureting-chamber. Simultaneously herewith the bucket *k* of an oscillatory scoop-device lifts a measured quantity of hydrocarbon from the reservoir *l* and empties it into a funnel *m*, located in a vessel *o*, whose spout *r* leads to the duct *h*. The vessel *o* contains a sealing-liquid *p*, into which the tube *n* of the funnel *m* dips, whereby an effective vapor-tight seal is formed.

At the top of the casing *7* of the gas holder, there is fulcrumed a pivotal lever *14* the free end of which rests upon the bell *g* of the gas holder in such a manner that as soon as the bell *g* is full the lever *14* actuates the lever system *15* and *15^a* the bar *15^a* of which is pivoted at *15^b* and carries a brake shoe *16* forcing the latter against the brake disk *17* arresting the disk and hence also a driving gear *c d*. When the bell *g* does not fill owing to the consumption of gas the brake is raised automatically and the apparatus thus supplies more gas.

The scoop device *k* which receives its movement from a rod *18* and eccentric *18^a* rotated by the gear wheels *c* and *d*, is also controlled by the lever system *15* and *15^a*. The rod *18* is connected with the arm *30* on the crank shaft *31*; and by means of a link *32* the crank shaft is connected with the scoop-device *k*. The generated gas flows through the pipe *11* into the space below the hood *f* and thence through the bell *g* of the outlet *12* leads the gas to the place of consumption.

Mercury, glycerin, or any other suitable slowly evaporable liquid may be used as sealing-fluid: and the mechanical details of the sealing-device may naturally be other than those illustrated by way of example in the drawing.

I claim:

An oil feeding device comprising an oil tank, a scoop, a sealing vessel, and oscillatory scoop-device.

latory means for intermittently operating said scoop for transferring a quantity of oil from said tank into said sealing vessel; said sealing vessel having an outlet spout 5 approximately midway between top and bottom of the vessel, a funnel closing the top of said sealing vessel for receiving the oil from said scoop, a pipe extending below said spout from said funnel, and a sealing

liquid reaching above the lower orifice of 10 said pipe in said vessel.

In testimony whereof I affix my signature in presence of two witnesses.

WALTER THIEM.
